(57) **CLAIM**

The ornamental design for a set of decorative letters, as shown and described.

DESCRIPTION

FIG. 1 is a front, right and top perspective view of the letter A of a set of decorative letters showing my new design; FIG. 2 is a rear, left and bottom perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; FIG. 8 is a bottom plan view thereof; FIG. 9 is a front, right and top perspective view of the letter B of a set of decorative letters showing my new design; FIG. 10 is a rear, left and bottom perspective view thereof; FIG. 11 is a front elevation view thereof; FIG. 12 is a rear elevation view thereof; FIG. 13 is a left side elevation view thereof; FIG. 14 is a right side elevation view thereof; FIG. 15 is a top plan view thereof; FIG. 16 is a bottom plan view thereof; FIG. 17 is a front, right and top perspective view of the letter E of a set of decorative letters showing my new design; FIG. 18 is a rear, left and bottom perspective view thereof; FIG. 19 is a front elevation view thereof; FIG. 20 is a rear elevation view thereof; FIG. 21 is a left side elevation view thereof; FIG. 22 is a right side elevation view thereof; FIG. 23 is a top plan view thereof; FIG. 24 is a bottom plan view thereof; FIG. 25 is a front, right and top perspective view of the letter K of a set of decorative letters showing my new design; FIG. 26 is a rear, left and bottom perspective view thereof; FIG. 27 is a front elevation view thereof; FIG. 28 is a rear elevation view thereof; FIG. 29 is a left side elevation view thereof; FIG. 30 is a right side elevation view thereof; FIG. 31 is a top plan view thereof;

(Continued)

FIG. 32 is a bottom plan view thereof;
 FIG. 33 is a front, right and top perspective view of the letter L of a set of decorative letters showing my new design;
 FIG. 34 is a rear, left and bottom perspective view thereof;
 FIG. 35 is a front elevation view thereof;
 FIG. 36 is a rear elevation view thereof;
 FIG. 37 is a left side elevation view thereof;
 FIG. 38 is a right side elevation view thereof;
 FIG. 39 is a top plan view thereof;
 FIG. 40 is a bottom plan view thereof;
 FIG. 41 is a front, right and top perspective view of the letter M of a set of decorative letters showing my new design;
 FIG. 42 is a rear, left and bottom perspective view thereof;
 FIG. 43 is a front elevation view thereof;
 FIG. 44 is a rear elevation view thereof;
 FIG. 45 is a left side elevation view thereof;
 FIG. 46 is a right side elevation view thereof;
 FIG. 47 is a top plan view thereof;
 FIG. 48 is a bottom plan view thereof;
 FIG. 49 is a front, right and top perspective view of the letter R of a set of decorative letters showing my new design;
 FIG. 50 is a rear, left and bottom perspective view thereof;
 FIG. 51 is a front elevation view thereof;
 FIG. 52 is a rear elevation view thereof;
 FIG. 53 is a left side elevation view thereof;
 FIG. 54 is a right side elevation view thereof;
 FIG. 55 is a top plan view thereof;
 FIG. 56 is a bottom plan view thereof;
 FIG. 57 is a front, right and top perspective view of the letter S of a set of decorative letters showing my new design;
 FIG. 58 is a rear, left and bottom perspective view thereof;
 FIG. 59 is a front elevation view thereof;
 FIG. 60 is a rear elevation view thereof;
 FIG. 61 is a left side elevation view thereof;
 FIG. 62 is a right side elevation view thereof;
 FIG. 63 is a top plan view thereof; and,
 FIG. 64 is a bottom plan view thereof.

The broken lines in the figures depict portions of the set of decorative letters that form no part of the claimed design.
